UNITED STATES PATENT OFFICE.

PAUL M. BEARD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

ALL-STEEL ROOF.

1,244,687.

Specification of Letters Patent. Patented Oct. 30, 1917.

Application filed February 10, 1915. Serial No. 7,446.

To all whom it may concern:

Be it known that I, PAUL M. BEARD, residing at St. Louis, Missouri, and being a citizen of the United States, have invented certain new and useful Improvements in All-Steel Roofs, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings:

Figure 1 is a plan view of part of a roof equipped with my invention.

Fig. 2 is a transverse sectional view, the section being taken on the line 2—2 of Fig. 1.

Fig. 3 is a transverse sectional view of a detail, the section being taken on the line 3—3 of Fig. 1.

Fig. 4 is an enlarged fragmentary detail view representing in full and dotted lines the manner in which the carline hereinafter referred to, is cut out and the purlin or ridge pole interlocked therewith in one construction.

Fig. 5 is a fragmentary plan view, showing in enlarged detail, the manner of securing the carline and carline anchor in position.

Fig. 6 is an elevational view of the parts shown in Fig. 5.

Fig. 7 is a sectional view, the section being taken on line 7—7 of Fig. 5.

Fig. 8 is an enlarged detail hereinafter referred to, and

Fig. 9 represents the relative location of the side-plate and roof sheets, hereinafter referred to, when the parts are assembled.

The invention consists of an all metal roof composed of roof sheets having a continuous upstanding flange on three sides, which flanges coöperate to hold the roof sheets in position, and a downturned flange on the fourth side at the eaves overlapping the side plate, but is spaced from such side-plate a short distance to allow a limited movement of the sheets, which are free to move under torsional stresses due to service conditions, as the sheets longitudinally of the car are

not riveted together, but are merely held together at the ridge over the purlin, or ridge pole, by means of U-shaped caps, shown in Figs. 3 and 8, which caps will be under the transverse cap or binding strip J, which latter is riveted to the carline, but, due to the contour of the carline, this transverse cap or binding strip has its longitudinal edges spaced from the carline a sufficient distance to allow the end of the roof sheet flange to lie therebetween and be held loosely in position.

The object of the invention is to provide a flexible all metal roof formed of parts so shaped and combined as to provide means for ventilating the interior of the car to which the roof is applied without the addition of special ventilating devices or ventilators.

Another object is to provide a roof comprising carlines, preferably formed of pressed metal, extending entirely across the roof from side-plate to side-plate and secured to such side-plates in such manner that the carlines, the carline-anchors securing the carlines in position, and the side-plates coöperate to form conduits leading to the interior of the car for purposes of ventilation.

The carline 10, the sectional contour of which is best indicated in Fig. 7, is formed as an inverted channel comprising a ridge portion 11, vertical flanges 12, horizontal flanges 13 and oblique depressed seat portions 14, on which seat portions rest the inturned edges 15 of the roof sheets 16, which roof sheets are flanged vertically upwardly, as indicated at 17, and are yieldingly locked in position by the binding strips J, before referred to, which are secured by the rivets 18 to the upper face of the carline.

Due to the contour of the carline and the edge portions of the binding strips J, seats are formed between the carlines and the edge portions of said binding strips, in which are loosely held the inturned flanges 15 of said roof sheets 16, in such manner that the binding strips prevent ingress of water between the roof sheets and the carlines, and at the same time permit such slight movement of the roof sheets, due to torsional stresses, as may be required.

Intermediate the ends of the carlines and at the points where they intersect the ridge pole 20, the carlines are cut out, as shown

at Figs. 2, 4 and 8, and the ridge pole is likewise cut away, as indicated in Figs. 2 and 4, if desirable, and carlines and ridge pole are secured together by means of tie straps 21, riveted to the lower flanges 13 of the carlines and the lower flanges 22 of the ridge pole.

Fig. 8 is a section on line 8-8 of Fig. 7 and is similar to Fig. 3, showing, in addition, the ridge pole cap 32 having flanges 31 lapping over the side flanges 17 on the roof sheets and, in turn, being overlapped by the binding strips J.

The ridge pole cap is reinforced by one or more corrugations 33.

The invention also comprises a new carline-anchor, best shown in Figs. 2, 5 and 6, which is especially adapted for connection to a flanged metallic car-side-plate, which 20 car-side-plate in the present construction is formed of a commercially rolled Z-section, though a flanged pressed section would answer, if desired.

Referring specifically to the carline-anchor in the figures noted, the bottom portion of such carline-anchor is of relatively box formation, comprising a bottom ledge 40, vertical wall 41, side walls 42, and an outstanding vertical wall 43, which latter 30 is preferably provided with a short inwardly projecting ledge 44, on which rests the carline before referred to.

The carline-anchor preferably rests upon the outstanding flange 46 of the Z-shaped side-plate 47, and is riveted thereto through the ledge 40 by means of the rivet 48 and, if desired, additional rivets, as 49, may extend through the vertical wall 41 of the carline-anchor into the web 50 of the car-side-plate.

Connecting the outstanding wall 43 with the vertical walls 41 of the carline-anchor, are inwardly extending walls 51, which with said wall 43 form a U-shaped pocket adapted to telescope with and be secured to the outstanding or upwardly projecting portions of the carlines.

To adapt the carlines for the connection above indicated, the horizontal flanges 13 thereof are cut through transversely of such flanges to the vertical web portions 12 in approximate vertical alinement with the outer face of the web 50 of said side-plate, and the partially severed fragments of such 55 flanges at the ends of the carlines are bent vertically downwardly so as to extend parallel, or substantially parallel, with the walls or flanges 51, before referred to, and the rivets 55, shown in Figs. 2, 5 and 6 secure 60 the vertical flanges 12 and the downturned portions of the flanges 13 to said walls 51, thereby firmly securing the carlines in position after which the roof sheets 16 are placed in position resting upon the outstanding flanges 13 of the carlines and being

seated in the pockets 14, between the carline and the binding strips J, as before noted.

Lugs on the inwardly extending walls 51 of the carline anchor are indicated at 56. 70 Their object being to provide a holding surface to prevent the roof sheets from sliding outwardly. As shown in Fig. 5 these lugs bear against the ends of the side flanges on the roof sheets. 75

Due to the thickness of the flanges 13, which rest upon the inturned flanges 46^a of the car-side plate, it will be noted that the roof sheets 16 are held in position above, but slightly removed from, the flanges 46^a 80 of said side-plate, thus providing clearance which will permit torsional movement of the roof sheets without undue friction against the side-plate.

The peculiar construction of the carline-anchor, in conjunction with the carline of inverted channel shape, provides a ventilated car roof supporting carline, which is closed at its outer end by means of the wall 43 of the carline-anchor, and due to the fact that said wall 43 is positioned outwardly from the vertical wall 41, a clear passage is provided for ventilation above the side-plate through the carline-anchor and outer end of the carline and into the interior of the 95 car, as indicated by the arrows in Fig. 2. 85

The wall 43 closes the outer open end of the carline to prevent ingress of water to the interior of the car and, due to the fact that such wall 43 extends downwardly below the upper face of the side-plate, the interior of the car is protected while leaving ample opening through the conduit thus formed for the necessary ventilation. 100

What I claim is:

1. In a ventilated car roof, a side plate, a carline anchor secured to the outer side thereof, projecting thereabove and provided with an outstanding wall, and a carline of inverted channel form passing over said side plate and having an open end portion closed by said outstanding wall and extending below the top of said side plate to be interlockingly retained between the same and said wall, said anchor and carline forming an air duct to a car interior. 110

2. In a ventilated car roof support, a side-plate of Z-shape, a carline-anchor secured thereto, said carline-anchor having means of attachment to said side-plate and 120 having a substantially U-shaped outstanding portion seated on one flange of said side plate and a carline of inverted channel shape telescoping with and adapted to have its end closed by said outstanding portion of 125 the carline-anchor, said carline resting upon the other flange of said side plate

3. In a ventilated car roof support, a side plate, a carline-anchor secured thereto having wall portions arranged to form a ven- 130

- tilating duct, said side plate having vertical and horizontal portions extending entirely across said carline-anchor and forming a seat therefor, and a car-line having a ventitating passage extending beyond said side plate vertical portion and inter-engaging with said carline anchor. 5
4. In a car roof, a side plate, a carline anchor on the outer side thereof comprising a lower laterally opening box-like formation having a closed bottom secured to said side plate and an upper U-shaped outstanding portion, a carline of inverted channel form resting upon and projecting above said side plate and into said upper U-shaped anchor portion to have its end closed thereby and to form with said anchor a dust-excluding ventilating passage to a car interior, and roof sheets lapping said carline and side plate. 10
5. In a car roof, a side plate, an inverted channel-shaped carline resting thereon, a cap secured to and extending longitudinally of said carline forming therewith longitudinal receiving grooves, roof sheets slideable longitudinally of said carline to their normal positions and having edge portions slideable in said receiving grooves, a carline anchor interlocked with said carline and secured to said plate preventing the withdrawal of said roof sheets. 15
6. In a ventilated car roof, a side-plate, a passage-containing carline-anchor secured thereto and having a bottom terminal lying on and fitting a bottom portion of said side plate that extends under said anchor bottom terminal and having an outstanding part spaced from said side plate, a carline overlapping said side-plate and having an open end adapted to be closed by the outstanding part of said carline-anchor, said carlinelapping and being secured to said carline-anchor, in combination with roof sheets resting upon said carline. 20
7. In a flexible car roof, carlines of inverted channel form to provide ventilating channels, side-plates, hollow carline-anchors 25
- resting upon the side-plates to provide continuations of the ventilating channels leading to the exterior of the car, flanged roof sheets supported by said carlines, and ears upon said carline-anchors bearing against the flanges on the roof sheets and preventing outward transverse movement of said sheets. 30
8. In a ventilated car roof support, a side plate, hollow carline anchors secured to said side plate and provided with carline seats, roof sheet-retaining means and with openings leading to the interior of the car, and channel shaped carlines having substantially inverted U shaped cross-sections and adapted to telescope at the outer ends with said carline anchors and to rest upon said seats in such manner that the channels of said carlines are continuations of the openings through said carline anchors, in combination with roof sheets suitably related to said carlines and roof sheet-retaining means. 35
9. In a flexible car roof, carlines having vertical side walls, flanges extending outwardly from said side walls, crown portions extending between said side walls, a side plate, means to secure the carlines to said side plate, in combination with a plurality of roof sheets having substantially vertical flanges at the side edges thereof provided with outwardly turned edges, and binding strips carried by the carlines and cooperating but not adapted to interfere with said outwardly turned edges to clamp the same against the crowns of said carlines with the vertical flanges of the roof sheets slightly spaced from the side walls of said carlines to form a flexible connection between the several carlines and roof sheets. 40
- In testimony whereof I have hereunto signed my name in the presence of two witnesses.

PAUL M. BEARD.
